UNITED STATES PATENT OFFICE.

ROBERT F. HALL, OF SCHENECTADY, NEW YORK.

LOCOMOTIVE.

Application filed January 13, 1923. Serial No. 612,406.

To all whom it may concern:

Be it known that I, ROBERT F. HALL, a citizen of the United States, and a resident of Schenectady, in the county of Schenectady and State of New York, have invented a certain new and useful Improvement in Locomotives, of which improvement the following is a specification.

My invention relates to locomotive engines of the type on which, through the intermediation of a cranked driving axle, more than two main or operating steam cylinders are installed, as in those known as three-cylinder and four-cylinder engines. The object of my invention is to enable increased economy in the consumption of steam, in locomotives of the types referred to, to be effected, without unduly increasing the diameter of the inside cylinder and the size and weight of the members connected therewith, the strength of which is a function of their diameters. A secondary object of my invention is to enable a reduction of the diameter of the inside cylinder to be effected, when a relatively longer maximum cut off is operated, for the purpose of limiting the size and weight of the parts.

The improvement claimed is hereinafter fully set forth.

In the accompanying drawings: Figure 1 is a diagrammatic side view, in elevation, of a three cylinder locomotive engine, embodying my invention; Fig. 2, a similar plan view of the same, showing the main connecting rods of all three cylinders as coupled to the same driving axle; Fig. 3, a similar view, showing the main rods of the inside and the outside cylinders as connected to different driving axles; Fig. 4, a front view, in elevation, showing all three cylinders as of equal diameters; Fig. 5, a similar view, showing the two outside cylinders as of greater diameter than the central cylinder; Fig. 6, a vertical longitudinal central section through a cylinder and its distribution valve chest; Figs. 7 and 8, ideal indicator diagrams, illustrating, respectively, steam as cut off at 50 per cent and at 85 per cent of the stroke of the piston; Fig. 9, a diagram showing the ordinarily preferred angular relation of the three cranks of a three cylinder locomotive; Fig. 10, an ideal turning moment diagram for a two cylinder engine with 85 per cent cut off; Fig. 11, a similar diagram for a three cylinder engine with 85 per cent cut off in all three cylinders;

Fig. 12, a similar diagram for a three cylinder engine, with 50 per cent in all three cylinders, the central cylinder being of smaller diameter than the outside cylinders; 60 and, Fig. 13, a similar diagram for a three cylinder engine, with 85 per cent cut off in the central cylinder and 50 per cent cut off in the outside cylinders, the central cylinder being of smaller diameter than the outside 65 cylinders and than the central cylinder referred to in the diagram Fig. 12.

Locomotive engines of the ordinary two cylinder type, have been designed, and are now operating satisfactorily in regular service, in which, for the purpose of effecting a greater ratio of expansion, while the engine is exerting its maximum tractive force, the maximum cut off has been caused to be made at, or not greater than, 50 per cent of the 75 piston stroke. The result of this limitation of the period of steam admission has been the effecting of more work, per unit weight of steam used, as compared with common practice, in which the maximum cut off is 80 about 85 per cent of the piston stroke. By the term "maximum cut off" is meant the greatest proportion of the piston stroke at which the admission of steam to the cylinders is permitted to be cut off by the distribution valve mechanism, and from which point the work done by the steam, in moving the pistons, is that due to its expansion in the cylinders. As shown by the indicator diagrams, Figs. 7 and 8, the points of cut-off, in the two diagrams, are *a* and *b*, respectively, which points are located at 50 per cent and 85 per cent, respectively, of the piston stroke, *c*. The areas of the diagrams are, as is well known in practice, proportionate to the net work done by the steam, during one stroke of the piston, corresponding to a half revolution of the crank pin, through 180 degrees.

The positions of a piston and its steam distribution valve, at the point of 50 per cent maximum cut off, are shown in Fig. 6, the piston 1° , being at the middle of its stroke, that is, having moved 50 per cent of its stroke in the cylinder, 1, and the distribution valve, 2, which is of the inside admission piston type, having closed the port, 1° , through which steam had been admitted to the cylinder, throughout the preceding half stroke of the piston, and having opened the port, 1° , through which steam from the opposite side of the piston is exhausted.

The valve operating mechanism by which the distribution valve is actuated, being well known in practice, and not forming, in and of itself, part of my present invention, is not herein exemplified. The mean effective pressure, which is the average net pressure acting on one side of the piston, throughout its stroke, is proportionate to the area of the indicator diagram, divided by its length, and is, approximately, 85 per cent of the initial pressure, in the case of an 85 per cent cut off, and 70 per cent in the case of a 50 per cent cut off.

In the operation of locomotives of the three cylinder and four cylinder types, having one or two inside cylinders, the piston or pistons of which is or are connected to a crank or cranks, on a driving axle, the "turning moment" is more uniform than that of the ordinary two cylinder locomotives, and it is therefore possible to obtain a greater exertion of power, relatively to adhesive weight, than in the two cylinder type. The term "turning moment" will be understood as meaning the product of the net force acting on the piston, at any given point of its stroke, multiplied by the length of the crank in its corresponding angular position, projected on a vertical line. It will be seen, by reference to the turning moment diagrams, Figs. 10 to 13, inclusive, that as the number of cylinders is increased, their combined turning moment becomes more uniform and the fluctuation between minimum and maximum power is reduced. Inasmuch as the work performed during a stroke varies directly as the mean effective pressure, it follows that, other things being equal, it is necessary to increase the piston area acted upon by this pressure, to approximately 21 per cent, to obtain equal power, when a 50 per cent maximum cut off is adopted instead of an 85 per cent, or otherwise, to increase the stroke in the same proportion, maintaining the same diameter, which would correspond to an increase of diameter of approximately 10 per cent.

Figs. 10 to 13 inclusive are ideal turning moment diagrams, Fig. 10 being illustrative of that in a two cylinder engine, with 85 per cent maximum cut off; Fig. 11, that in a three cylinder engine, with 85 per cent maximum cut off in all three cylinders; Fig. 12, that in a three cylinder engine, with 50 per cent maximum cut off in all three cylinders, the central cylinder being of smaller diameter than the two outside cylinders; and, Fig. 13, that in a three cylinder engine, with 85 per cent maximum cut off in the central cylinder and 50 per cent maximum cut off in the two outside cylinders, the central cylinder being of smaller diameter than the two outside cylinders and than the central cylinder of Fig. 12. Ordinates in these diagrams will be proportionate to the combined

turning moment of all the cylinders and horizontal distances proportional to the angular position of the cranks, the total distance representing one complete revolution, or 360 degrees change in angular position.

The more uniform turning moment in the three cylinder engine, will be apparent from these diagrams, and it will also be noted that while the turning moment indicated in Fig. 12, is not as uniform as that in Fig. 11, and shows greater fluctuation between maximum and minimum, there is, nevertheless, a much lower range of fluctuation between maximum and minimum than in the case of the two cylinder engine, Fig. 10.

The relation known as the "factor of adhesion," which is obtained by dividing the adhesive weight of the locomotive, by its tractive force, is approximately 4 to 4.5 in two cylinder engines, and in some cases, where the boiler power is larger, in proportion to that of the cylinders, this factor may reach the value of 5 or more. The value of the factor of adhesion is an approximate measure of the relation between the capacities of the boiler and the cylinders, and, as this factor may, in some cases, be as low as 3, on three cylinder engines, it will be seen that the boiler capacity of this type of engine is a materially important consideration. If the cylinders of an engine of such type be made of sufficient capacity to utilize a greater proportion of the adhesive weight of the locomotive, it is difficult to provide boiler capacity sufficient for the supply of three cylinders, and, while economy in the use of steam is of prime importance in any type of locomotive, it is particularly desirable in the case of three and four cylinder engines for this reason.

My invention is based upon, and is the result of, an extended consideration of the operative conditions and practical requirements hereinbefore explained, in locomotive engines of the types to which it relates, and its leading and characteristic feature consists in a novel disposition, hereinafter explained, of the relative capacities of the inside and outside cylinders, whereby a comparatively short maximum cut off may be operated, with the result of developing the maximum boiler capacity and tractive force of the locomotive, with an economical consumption of steam, and with a minimum diameter of the inside cylinder and its connected members. A further result, of substantial importance, of the disposition referred to, is the attainment of a total higher cylinder power than would be possible in the case where all three cylinders are of equal capacity, in which case structural conditions impose a limitation upon the increase of diameter or stroke of the middle cylinder.

In the practice of my invention, referring

descriptively to the specific embodiment thereof which is herein exemplified, as applied in a three cylinder single expansion locomotive of the "Mountain" type, having a central cylinder, 1, and two outside cylinders, 1^a, 1^b; the central cylinder, 1, is made of greater capacity than would be, if operated with a maximum cut off of say, 85 per cent, required in the case where the three cylinders are of equal diameters, but of less capacity than would be required in the case where the three cylinders are of equal diameters and operated with a maximum cut off of, say, 50 per cent. In order to compensate for such reduction of capacity of the central cylinder, the outside cylinders are made of greater capacity than would be necessary if all three cylinders were of equal diameters and operated with a maximum cut off of, say, 50 per cent. For example, let there be considered a three cylinder engine, all the cylinders of which are of equal capacities, as in present practice, and as indicated by being shown of equal diameters in Fig. 4, as, say, 24 inches, the valve gears being adapted to effect a maximum cut off in full gear, of 85 per cent. Three cylinders, of approximately 26½ inches in diameter, would be necessary in order to develop equal power with a maximum cut off of 50 per cent. By making the central cylinder 25 inches in diameter, and the two side cylinders each 27 inches in diameter, the same power can be developed, in full gear, with maximum cut off of 50 per cent in all three cylinders.

The pistons, 1^c, of all the cylinders, are, as in ordinary practice, coupled by main connecting rods, 1^d, to the crank pin of a crank, 9, on a main driving axle, 9, either directly, as shown in Fig. 2, or through the intermedium of side or coupling rods, 10, as shown in Fig. 3. Steam is supplied from the boiler, 11, to the distribution valve chests, 2^e, through which it is admitted to, and exhausted from, the cylinders, by the distribution valves, 2. Various types of valve gear, by which said valves may be operated to effect the cut off desired, are well known in standard practice, and not, in and of themselves, forming part of my present invention, are not herein exemplified. Fig. 9 indicates the crank pins of the three cylinders as set in the symmetrical angular relation of 120 degrees apart, but while such location is ordinarily the preferred one, it may, in some cases, be found advisable to vary it in practice, and it is not an essential of my invention.

A still further reduction in the diameter of the central cylinder, and in the dimensions and weight of its allied members, may be effected by adjusting the valve gears so as to effect a longer cut off, as, say, 85 per cent, in the central cylinder, and a shorter maximum cut off, as, say, 50 per cent, in the outside cylinders. This manner of operation would admit of the application of a central cylinder, 23 inches in diameter and outside cylinders 27 inches in diameter, or a central cylinder 24 inches in diameter, and outside cylinders 26½ inches in diameter. The same power would then be obtained as in the operation of three cylinders, all of approximately 26½ inches in diameter, with a maximum cut off of 50 per cent, as in the instance before referred to.

A reduction in the diameter of the central cylinder may also be effected by increasing the stroke of its piston, relatively to that of the pistons of the outside cylinders. The decrease of the diameter of the central cylinder being in the same proportion as the increase of piston stroke, a uniform cut off may be operated in all three cylinders. However, inasmuch as the result of change of length of stroke varies as the first power, while that of change of diameter varies as the square, a change in diameter will, for this reason be found preferable. It will be obvious that other variations of point of cut off; stroke of piston; and relative cylinder dimensions, may be made without departure from the spirit and operative principle of my invention.

In the operation of two cylinder locomotives in which the maximum cut off is structurally limited to 50 per cent, there are four crank pin positions in each revolution from which the engine will not start, when steam is initially admitted to the cylinders from the boiler. This objection is overcome by the provision of what is termed a "trick port" through which a small amount of steam is admitted before the distribution valve has reached its normal admission port. This device ensures the starting of the engine from any crank pin position, and while necessary in a two cylinder engine, it is, to a certain extent, objectionable, and it is not required in three or four cylinder engines.

I claim as my invention and desire to secure by Letters Patent:

1. In a single expansion locomotive, the combination of a cranked driving axle; a central cylinder; and two outside cylinders, the pistons of all of which cylinders being coupled to said driving axle, and the capacity of the central cylinder being less than that of either of the outside cylinders.
2. In a single expansion locomotive, the combination of a cranked driving axle; a central cylinder; and two outside cylinders, the pistons of all of which cylinders being coupled to said driving axle, and the diameter of the central cylinder being less than that of either of the outside cylinders.
3. In a single expansion locomotive, the combination of a cranked driving axle; a central cylinder; two outside cylinders, the pistons of all of which cylinders being coupled to said driving axle, and the capacity of the central cylinder being less than that of either of the outside cylinders.

pled to said driving axle, and the diameter of the central cylinder being less than that of either of the outside cylinders; and means for effecting a comparatively short maximum cut off, as not exceeding 50 per cent, in said cylinders.

4. In a single expansion locomotive, the combination of a cranked driving axle; a central cylinder; two outside cylinders, the 10 pistons of all of which cylinders being coupled to said driving axle, and the diameter

of the central cylinder being less than that of either of the outside cylinders; means for effecting a comparatively short maximum cut off, as not exceeding 50 per cent, in the 15 outside cylinders; and means for effecting a substantially longer maximum cut off in the central cylinder.

ROBERT F. HALL.
